UNITED STATES PATENT OFFICE.

FRED J. RANFORD, OF OSWEGO FALLS, NEW YORK.

WHEEL.

SPECIFICATION forming part of Letters Patent No. 692,710, dated February 4, 1902.

Application filed March 27, 1901. Serial No. 53,067. (No model.)

To all whom it may concern:

Be it known that I, FRED J. RANFORD, of Oswego Falls, in the county of Oswego, in the State of New York, have invented new and 5 useful Improvements in Wheels, of which the following, taken in connection with the accompanying drawings, is a full, clear, and exact description.

My invention relates to improvements in 10 wheels, and particularly to split wood pulleys.

The object of this invention is to produce a light and durable pulley which may be manufactured at a minimum cost and may be readily and economically assembled or disas- 15 sembed.

The further object of my invention is to 20 permit one of the sections of the rim to be removed when desired without disturbing the position of the clamping-bars upon the shaft 25 or, in other words, without disturbing the alinement of the pulley.

A still further object of this invention is to 25 permit one of the pairs of clamping-bars to be inserted or withdrawn laterally or axially 30 into and out of operative position without disturbing the other clamping-bars or affecting the alinement of the pulley.

To this end the invention consists in the 35 construction, combination, and arrangement 40 of the component parts of a pulley, as hereinafter fully described, and pointed out in the claims.

Referring to the drawings, Figure 1 is a side 45 elevation of my improved pulley, portions 50 thereof being broken away for disclosing the tenons of the clamping-lugs. Figs. 2 and 3 are respectively a face view and a sectional view taken on line 3-3, Fig. 1, one of the quarter rim-segments being removed in Fig. 2. 55 Fig. 4 is an isometric view of two of the adjacent lugs, showing the staggered relation of their tenons. Figs. 5 and 6 are detached views of the lugs seen in Fig. 4.

Similar reference characters indicate cor- 60 responding parts in all the views.

As seen in the drawings, my improved pulley consists, essentially, of a rim 1, inner and outer clamping-bars 2 and 3, lugs 4, lapping upon the outer ends of the clamping-bars 2 65 and 3, and additional lugs 5, lapped upon the outer ends of the lugs 4.

The rim 1 is preferably formed of wood

composed of a series of layers glued or otherwise secured together face to face and is split transversely in intersecting planes at 55 substantially right angles to each other for forming a series of quarter-segments, the meeting edges of which are provided with a series of projections and depressions for forming interlocking shoulders which serve to 60 stiffen the rim and to prevent lateral displacement of the meeting edges of said segments. These shoulders preferably consist of the extended ends of some of the layers which form the rim of the pulley. This 65 method of interlocking the meeting edges, however, being of minor importance, it is not believed to be necessary to further illustrate or describe the same. The meeting ends of each of these segments are each provided with 70 apertures or sockets 8 and 8', which are generally arranged in pairs in staggered relation to each other for receiving tenons 9 and 10, formed, respectively, upon the outer ends of the lugs 4 and 5, said tenons being also ar- 75 ranged in staggered relation to each other and are secured within the apertures 8 and 8'. These tenons are usually of substantially the same width and are arranged in alinement with adjacent layers of the rim of the 80 pulley. The tenons 9 are formed, as previously stated, upon the lugs 4 and are usually of less width than said lugs for forming the shoulders 11, which engage the inner faces 85 of the rim-segments to give more bearing for the lugs.

The lugs 4 are preferably arranged in pairs at opposite sides of the meeting faces of the rim-segments, the adjacent faces of each pair being substantially parallel and separated 90 from each other for receiving the ends of the clamping-bars 2 and 3 and are formed with suitable apertures for receiving the clamping-bolts, presently described.

The lugs 5 are preferably formed of less 95 length than the lugs 4, are also arranged in pairs at opposite sides of the meeting edges of the rim-segments, and are lapped upon the opposite faces of the lugs 4, being of greater width than their tenons 10 for forming suitable shoulders 12, which are also engaged with the inner faces of the rim-segments and serve to better brace said lug.

It is apparent from the foregoing descrip-

tion that the lugs 4 and 5 at each end of the rim-segments abut one against the other, that their tenons 9 and 10 are arranged in staggered relation to each other and extend 5 through the rim, being formed of substantially the same length as the thickness of the rim, and that the rim is thus provided with diametrically opposite lugs extending inwardly toward each other, the lugs 4 adjacent to the 10 meeting edges of the rim-sections being extended inwardly a greater distance than the lugs 5, and by thus securing the lugs to the rim and forming the same as just described the adjacent ends of the clamping-bars and 15 rim-segments are materially stiffened and the strain is transmitted more evenly from the rim to the clamping-arms and from the clamping-arms to the rim, thereby forming a more perfect pulley and adapting the same to better 20 resist the strain incidental to the engagement of the belt therewith.

The clamping-bars 2 and 3, as previously stated, are arranged in pairs, the bars of one pair being disposed in a plane at substantially 25 right angles to the bars of the other pair, said bars of each pair being arranged at opposite sides of a suitable shaft, as 14, and adapted to be frictionally engaged therewith by suitable clamping-bolts or other equivalent means 15.

As seen in the drawings, I have shown two 30 pairs of the clamping-bars 2, being arranged side by side in the direction of the axis of the pulley, with their adjacent faces in close contact and their opposite ends inserted between 35 the diametrically opposite pairs of lugs 4, it being understood that there are one set of lugs for the adjacent ends of each pair of the clamping-bars. These clamping-bars are formed of substantially the same length as the 40 inner diameter of the pulley, their end faces being adapted to engage the inner faces of the meeting ends of the segments of the rim and serving to materially stiffen the adjacent ends of the rim-segments and also to relieve the 45 strain upon the clamping-bolts previously mentioned.

The clamping-bars 3 are also arranged in pairs at opposite sides of the clamping-bars 2, the inner faces of the bars 3 being disposed 50 in close proximity to the outer faces of the bars 2, the bars 3 of each pair being arranged at opposite sides of the axle or shaft 14 and are clamped upon the shaft by suitable clamping-bolts 15'. The opposite ends 55 of these clamping-bars 3 are interposed between diametrically opposite lugs 4, there being a set of lugs for each end of each pair of clamping-bars 3. These bars 3 are also formed of substantially the same length as 60 the inner diameter of the pulley and serve the same purpose as the clamping-bars 2, and it will be understood that by employing two sets of clamping-bars at right angles to each other the clamping-bars of one set may be removed 65 without displacing the clamping-bars of the other set if it is desired to remove

one-half of the pulley or one of the quarter segments.

The means for drawing the meeting edges of the rim-sections together consist of the 70 clamping-bolts 17 and 18, the bolts 17 being passed through apertures formed, respectively, in the lugs 5 and 4 at opposite sides of the meeting edges of the rim-sections and the adjacent ends of the clamping-bars 2 and 75 3, and the bolts 18 are passed through apertures formed in the lugs 4 at opposite sides of the meeting edges of the rim-sections and also through the adjacent ends of the clamping-bars 2 and 3. It is therefore evident that 80 when the lugs are drawn together by the bolts 17 and 18 the adjacent ends of the clamping arms or bars are firmly impinged between the lugs 4 and form a substantially integral pulley. 85

In assembling the parts of my invention the clamping-bars 2 and 3 are placed upon the shaft at substantially right angles to each other and when located in the desired position are securely clamped to the shaft by the bolts 90 15 and 15'. The rim sections or segments are then placed in position, and their meeting edges are drawn together by the bolts 17 and 18, which also secure the rim-sections to the clamping-bars 2 and 3. 95

If at any time it may be desired to remove one of the segments, it is simply necessary to remove the bolts 17 and 18, whereupon the desired segment may be readily withdrawn in a substantially radial direction. 100

In order to permit either of the quarter rim-sections to be removed independently of the others when the pulleys are of small diameter, I usually provide the rim with cut-outs or apertures 17', alined with the bolt 17, 105 which allows said bolt to be removed endwise through said apertures, or at least a sufficient distance to clear the lugs 4 of the sections to be removed. The bolts 18, which clamp the sections in position, may then be removed or 110 at least withdrawn a sufficient distance to clear the lugs 4 of the section to be removed, whereupon said section may be readily withdrawn. It should be understood, however, that in large pulleys the formation of the apertures 17' is unnecessary. I also provide the arms 2 and 3 of the small pulleys with slots 17'', which are extended outwardly to the end faces of said arms from the apertures which receive the bolts 17. The slot 17'' may 115 also be dispensed with in large pulleys or in such sizes of pulleys as will permit the bolts 17 to be withdrawn in either direction a distance equal to the combined thickness of the lugs 4 and 5 in addition to the thickness of 120 the nut at the end of the bolt, or, in other words, to permit the bolt to be withdrawn endwise a sufficient distance to clear the inner face of the lug 4 without striking the inner face of the rim. 125

The operation of my invention will now be readily understood upon reference to the 130

foregoing description and the accompanying drawings, and it will be noted that some change may be made in the detail construction and arrangement of the parts of my improved pulley without departing from the spirit of this invention.

Having thus described my invention, what I claim, and desire to secure by Letters Patent, is—

10 1. A wheel comprising axle-clamping bars, and a split rim having the meeting ends of its sections each provided with lugs having staggered tenons extending through the rim and secured to the bars.

15 2. The combination with a diametrically split rim, the meeting ends of each half-section being each provided with an inwardly-projecting lug, clamping-bars having their opposite ends interposed between the lugs, and

20 their intermediate portions arranged to engage opposite faces of the shaft and means for drawing adjacent lugs toward each other into engagement with the bars.

25 3. A wheel comprising a diametrically split rim having the meeting ends of its sections each provided with inwardly-projecting lugs tenoned into the rim in staggered relation to each other, and shaft-clamping bars having their opposite ends impinged between the adjacent lugs of the opposite rim-sections.

30 4. A wheel comprising a diametrically split rim having the meeting ends of its sections each provided with inwardly-projecting lugs tenoned into the rim in staggered relation to each other, clamping-bars having their opposite ends interposed between the adjacent lugs of the opposite rim-sections.

35 5. A wheel comprising a diametrically split rim having the meeting ends of its sections each provided with inwardly-projecting lugs tenoned into the rim in staggered relation to each other and clamping-bars having their opposite ends interposed between opposite adjacent lugs of each section and their intermediate portions adapted to engage a shaft, and means for clamping the lugs and arms together.

40 6. A wheel comprising a diametrically split rim having the meeting ends of its sections each provided with inwardly-projecting lugs tenoned into the rim in staggered relation to each other, and clamping-bars having their opposite ends interposed between opposite adjacent lugs of each section and their end faces abutting against the inner faces of the meeting ends of said sections, the intermediate portions of the bars being arranged to engage the opposite faces of the shaft for the purpose set forth.

45 7. A wheel comprising a diametrically split rim having the meeting ends of its sections each provided with inwardly-projecting lugs tenoned into the rim in staggered relation to each other, and clamping-bars having their opposite ends interposed between opposite adjacent lugs of each section and clamping-

bolts passed through the opposite ends of the bars and the lugs adjacent thereto for drawing the rim-sections and for impinging the ends of the bars between the lugs.

50 8. A wheel comprising a rim formed of quarter-segments having their meeting ends formed with inwardly-projecting lugs, and independent pairs of clamping-bars each having their opposite ends inserted between diametrically opposite lugs.

55 9. A wheel-rim split transversely in intersecting planes for forming quarter rim-segments, in combination with independent pairs of clamping-bars arranged at substantially right angles to each other and having their meeting faces alined respectively with the opposite meeting faces of the rim-segments, and means for detachably securing the bars to the segments.

60 10. The combination with the sections of a split rim, each section being provided with inwardly-projecting lugs in proximity to its end faces, clamping-bars having their opposite ends inserted between the adjacent lugs and their end faces abutting against the inner faces of the meeting ends of the sections, and means engaged with the adjacent lugs for drawing the rim-sections together and thereby clamping the opposite ends of the bars between adjacent lugs.

65 11. The combination with opposite axle-clamping bars, of a split rim having the meeting faces of its sections in substantial alinement with the adjacent meeting faces of the bars, the inner faces of the meeting ends of the rim-sections being engaged with the end faces of the bars and provided with inwardly-projecting lugs engaged with the arms and detachably secured thereto.

70 12. The combination with opposite axle-clamping bars, of a split rim having the meeting faces of its sections in substantial alinement with the adjacent meeting faces of the bars, the inner faces of the meeting ends of the rim-sections being lapped upon the end faces of the bars and provided with inwardly-projecting lugs lapped upon the arms, and means engaged with the lugs for drawing the rim-sections and bars together.

75 13. The combination with opposite axle-clamping bars, of a split rim having the meeting faces of its sections in substantial alinement with the adjacent meeting faces of the bars, the inner faces of the meeting ends of the rim-sections resting upon the end faces of the bars and provided with inwardly-projecting lugs engaged with the arms and detachably secured thereto, and means for forcing the intermediate portions of the bars toward each other for the purpose described.

80 14. The combination with independent pairs of clamping-bars arranged in intersecting planes and formed of substantially the same length, of a rim divided in alinement with the meeting faces of the bars of each pair, lugs tenoned in the rim-segments of the rim in proximity to their meeting faces, and

means for detachably securing the ends of the bars to the adjacent lugs.

15. A wheel comprising a split rim, the meeting ends of its sections being each provided with lugs tenoned in the rim in staggered relation to each other, clamping-bars having their opposite ends inserted between adjacent opposite lugs, said bars being removable endwise of the wheel, and means for detachably securing the bars to the lugs.

16. A wheel comprising a rim having opposite pairs of inwardly-projecting lugs tenoned in the rim, said rim being split between the

lugs of each pair, and clamping-bars removable endwise of the wheel and having their opposite ends inserted between the lugs of each pair, either of the sections being removable independently of the bars, and means for clamping each pair of lugs to the adjacent ends of the bars.

In witness whereof I have hereunto set my hand this 4th day of March, 1901.

FRED J. RANFORD.
